UNITED STATES PATENT OFFICE.

ZACHARY TAYLOR HARTMAN, OF PHILADELPHIA, PENNSYLVANIA, AS-
SIGNOR OF ONE-HALF TO PHILIP WUNDERLE, OF SAME PLACE.

CANDY-DROPPING MACHINE.

SPECIFICATION forming part of Letters Patent No. 380,108, dated March 27, 1888.

Application filed September 14, 1887. Serial No. 249,620. (No model.)

To all whom it may concern:

Be it known that I, ZACHARY TAYLOR HARTMAN, a citizen of the United States, residing in the city and county of Philadelphia, State 5 of Pennsylvania, have invented a new and useful Improvement in Candy-Dropping Machines, which improvement is fully set forth in the following specification and accompanying drawings.

10 My invention consists in novel improvements in candy-dropping machines, as will be hereinafter fully set forth and definitely claimed.

15 Figure 1 represents a perspective view of a candy-dropping machine embodying my invention. Fig. 2 represents a vertical section of a portion in line x x , Fig. 4, on an enlarged scale. Fig. 3 represents a perspective view of the cut-off mechanism on an enlarged scale.

20 Fig. 4 represents an end view of a detached portion on an enlarged scale. Fig. 5 represents an end view of the cut-off arm on an enlarged scale. Fig. 6 represents a side elevation of the apron-operating mechanism on an enlarged scale. Fig. 7 represents different shapes of candy that may be dropped. Figs. 8 and 9 represent views of detached portions.

Similar letters of reference indicate corresponding parts in the several figures.

30 Referring to the drawings, A represents the frame of the machine, on which is supported the box B, containing candy-making material.

C represents the driving-pulley, on the shaft of which is a pulley or sprocket-wheel, a. (Shown 35 in dotted lines, Fig. 1.) Passing around said wheel a is a belt or band, D, which also passes around a sprocket-wheel, b, the latter having its shaft c mounted on the frame A, and carrying a sprocket-wheel, d, around which passes a belt or band, E, which also passes around a sprocket-wheel, e, on a shaft, F, the latter being mounted on the frame A and having its ends keyed or otherwise connected with eccentrics G, which are fitted within the yokes H 40 of arms J of the cut-off mechanism, as will be hereinafter specified.

To the shaft c is secured a slotted link, K, with which is connected one end of a pitman or rod, L, whose other end is pivoted to an

arm, M, which is freely mounted on the journal of the roller N of the apron P, and carries a pawl, Q, which engages with the ratchet R, which is fixed to said journal.

It will be seen that when power is applied to the pulley C motion is communicated to the belts D E, the sprocket-wheels b e, and consequently to the shafts c F. The arms J receive vibrating motions, and the link K rotates. Owing to the pitman L, arm M, ratchet and pawl R Q, the roller N is operated, and the apron P receives intermittent motion.

Attached to a wrist-pin on the wheel b is a bar or rod, S, which is connected with an elbow-lever, T, loosely fitted on a shaft, U, the latter being mounted above the apron P and 65 having firmly secured to it a ratchet, V, with which engages a pawl, W, hung on said elbow-lever T.

To the inner end of the shaft U is secured a bevel-pinion, X, which meshes with a bevel-wheel, Y, the latter being internally threaded and fitted on a sliding screw-shaft Z, whose bearings are on the cap of the box B and on brackets f, connected with said end, the wheel Y being located between said brackets, where- 70 by it is permitted to rotate and impart rotary and sliding motions to the shaft Z.

The inner end of the shaft Z is swiveled to the plunger A', which is located within the box B and presses against the material therein, 80 so as to eject the same through the openings g at one end of the box, it being noticed that the box is located above the apron P, and the latter is permitted to move freely beneath said box. Within the box are gates or valves B', 85 for closing the openings g when so required. Said openings may be of various configurations, different forms of candies as shaped thereby being shown in Fig. 7.

It will be seen that as the shaft U is operated the wheel Y is intermittently rotated, so that the shaft Z is similarly rotated and moved, and the plunger A' advances at intervals against the material in the box and forces the same in streams from the box owing to the openings g. 95 The material now requires to be cut off, the pieces then dropping on the apron P. This is accomplished by means of a wire or cutter,

C', whose ends are attached to arms D' on a shaft, E', which is mounted in sliding boxes F', which rise and fall in obliquely-arranged brackets G', secured to the frame of the machine, said shaft being also mounted in the arms J. Secured to the shaft E' are vertically-arranged levers H', whose upper ends are freely engaged by pins J', secured to the top of the vibrating arms J, the motions of the latter being accomplished by means of the eccentrics G, as has been stated. On the sides of the arms D' are studs D², carrying rollers or bearing-pieces D³, which are adapted to be engaged by the lower ends, H², of the levers H'.

15 H³ are vertical pieces or guides which are secured to the brackets H⁴, rising from the frame A, said guides being inclined, or having one side, H⁵, inclined, the studs D² riding on said inclined or oblique sides H⁵.

20 It will be seen that owing to the vibrating motions of the arms J the pins J' are alternately pressed against the levers H', and the shaft E' is raised and lowered by said vibrating arms J, the sliding boxes F' permitting 25 said shaft to rise and fall. Now, owing to the obliquely-arranged brackets G' and the studs D' riding on the oblique sides of the guides H', the arms D' carry the wire C' in oblique directions in the rising and falling motions

30 thereof. When the levers H' are pressed by the pins J', the lower ends, H², of said lever are raised and strike the rollers D², thus elevating the arms D'. When said levers are relieved of the pressing action of said pins, the 35 lower ends of said levers are lowered, whereby the arms D' are permitted to descend. By these means the wire is advanced to the discharge end or openings g of the box B, and descends along the same in contact therewith.

40 Now, as the projected streams of candy material are in the path of the descending wire, the latter cuts said material in lengths or pieces, which drop upon the intermittently-moving apron P, which carries pieces of paper, tins, or 45 plates to receive the dropped candy, so that the latter may be readily removed. (See Fig. 1.) After the wire has passed the openings g, it is carried backward, so as to clear the box, then raised, and again advanced toward the 50 box, where it descends and cuts the material, as before stated, the motion described by the wire being approximately that shown by the dotted lines in Fig. 5.

The wire C has its ends connected with the 55 heads of screws K', which are fitted to the arms D', so that the tension of the wire may be adjusted, said wire also bearing against the heads of screws L', which are secured to the arms D' at a right angle to the screws K', 60 whereby the wire may be nicely sustained and properly set out from said arms D'.

In order to hold the paper, tins, &c., on which the candy is dropped I employ springs M', each of which is connected at one end with 65 a staple, N', or other fastening on the frame A, (see Fig. 3,) the opposite end bearing down-

wardly against the paper. An arm, P', is connected with the spring and hung loosely from a cross-bar, Q', which joins the arms D', so that when the latter are operated the springs 70 are raised and lowered, so as to bear against and be released from the paper, whereby the paper is firmly held on the apron as the candy is dropped thereon, and released as the apron receives motion to carry away said paper as 75 supplied.

R' represents a roller for preventing upward motion of the apron and the sheet, &c., placed thereon.

Having thus described my invention, what I 80 claim as new, and desire to secure by Letters Patent, is—

1. A candy-dropping machine consisting of a frame, with the box B, having the openings g in one end thereof, the driving-pulley C, the 85 sliding plunger A' in said box B, the screw-shaft Z, swiveled to said plunger, the internally-threaded wheel Y, located on said shaft, mechanism, substantially as described, intermediate said wheel Y and said driving-pulley 90 C, for imparting rotary motion to said shaft Z, a movable apron, a cutter, and mechanism, substantially as described, for operating said cutter, said parts being combined substantially as and for the purpose set forth. 95

2. A candy-dropping machine having a cutter, a rising-and-falling shaft, arms secured to said shaft and provided with studs, vibrating arms and brackets with sliding boxes, the said rising-and-falling shaft being journaled in said 100 vibrating arms and boxes, and inclined guides, said parts being combined substantially as and for the purpose set forth.

3. The cutter C', in combination with the arms D', shaft E', sliding boxes F', obliquely-arranged brackets G', oscillating arms J, and pins J', substantially as described. 105

4. The arms D', having the studs D² and rollers D³, and carrying the cutter C', the levers H' H², the shaft E', carrying said arms and 110 levers, the inclined guides H⁵, and mechanism, substantially as described, connected to said shaft E', for imparting a rising-and-falling motion to the same, said parts being combined substantially as and for the purpose set 115 forth.

5. The shaft F, carrying the eccentrics G, in combination with the oscillating arms J, fitted on said eccentrics, the pins J', secured to said arms, the shaft E', the arms D', supported on said shaft E', the brackets G', the sliding boxes F', fitted in said brackets, and the cutter E', connected with said arms, the shaft E' being mounted in said sliding boxes, and oscillating arms, substantially as de- 125 scribed.

6. In a candy-dropping machine, the rotary shaft F, in combination with the arms J, the eccentrics G and pins J', the brackets G', with sliding boxes F', the shaft E', journaled in 130 said sliding boxes, the levers H' H², the arms D' with studs, the guides with inclined faces

H', the arms D', and the cutter C', secured to said arms D', substantially as and for the purpose set forth.

7. In a candy-dropping machine, the arms D', with cutter C' mounted on the shaft E', in combination with mechanism for imparting a rising-and-falling motion to said shaft, the

cross-bar Q', the arm P', the spring M', and a movable apron, substantially as and for the purpose set forth.

ZACHARY TAYLOR HARTMAN.
